UNITED STATES PATENT OFFICE

ERNEST A. CHANDLER AND JOHN H. McCANN, OF NASHVILLE, TENNESSEE

SHIFTABLE OVEN RACK

Application filed March 27, 1930. Serial No. 439,461.

This invention relates to improvements in racks for use in ovens or similar enclosed bodies and pertains particularly to a shiftable rack structure adapted to be connected with the door of the oven and to be moved outwardly therefrom when the door is opened and replaced therein when the door is closed.

The primary object of the present invention, in addition to the provision of a rack or racks shiftable with and by the door of the body in which they are mounted, is to provide an improved type of shiftable frame which is adapted to carry a pair of racks, one thereof being completely removable from the frame so that the other may be used alone in the oven when the maximum capacity of the oven is to be made use of.

Another object of the invention is to provide a rack or tray supporting frame of unique design, it being so constructed that side members thereof may act as runners in guide grooves or tracks, while a rear portion thereof which is disposed in an offset plane with respect to the side portions, may be employed for supporting one side of the oven rack.

Other objects and advantages of the present invention will become apparent as the description of the same proceeds and the invention will be best understood from a consideration of the following detailed description taken in connection with the accompanying drawings forming part of the present invention with the understanding, however that the invention is not confined to any strict conformity with the showing of the drawings but may be changed or modified so long as such changes or modifications mark no material departure from the salient features of the invention as expressed in the appended claims.

In the drawings:—

Figure 1 is a vertical sectional view through an oven showing the door thereof open and the racks in drawn out position.

Figure 2 is a sectional view similar to Figure 1 showing the door closed and the racks within the oven.

Figure 3 is a sectional view taken substantially upon the line 3—3 of Figure 2.

Figure 4 is a horizontal sectional view through one side of the closed oven looking down upon the racks.

Referring more particularly to the drawings wherein like numerals of reference indicate corresponding parts throughout the several views, the numeral 1 indicates generally an ordinary type of stove or range body showing therein the casing 2 which constitutes the oven. The front or open part of the oven may be closed by the use of the door 3 which is hingedly attached to the bottom edge thereof in the usual manner, as indicated at 4.

Secured horizontally to the inner face of each of the side walls 5 are the upper and lower track members 6 and 7 respectively, which as shown in Figure 3 are formed integral with a plate 9, the upper edge of which has formed intermediate the ends thereof the ear 10 through which a set screw 11 is passed into the adjacent wall of the oven to maintain the plate in position while the lower edge has adjacent its inner end a hook 12 which is engaged over one of a pair of pins 13 on the adjacent wall, and a notched lug 14 adjacent the outer end which is engaged over the other pin projecting from the adjacent wall.

Adjacent the inner end of each upper track 6 there is formed upon the upper face thereof a cam 15.

Slidable into the oven with its sides in the recess formed between the spaced track members 6 and 7 at the sides thereof, is a frame that is indicated as a whole by the numeral 16. This frame in plan view presents a substantially U-shaped outline, each side bar or leg 17 thereof being arranged with its outer edge slidably positioned between a pair of tracks 6 and 7 as shown. The cross bar 18 which connects the inner ends of the bars or legs 17 is arranged in a lower plane than the side bars and is connected thereto through the medium of the members 19 which, when the frame is in position, depend from the side bars 17 in the manner shown. At their free forward ends the side bars 17 have short

portions 20 set inwardly as shown in Figure 4.

Adjacent the rear of the slidable frame 16 each bar or leg 17 thereof carries an upwardly directed ear 21 which as shown in Figure 3 is spaced from the adjacent wall of the oven and carries an outwardly projecting pin 22.

The pin 22 of each ear 21 is slidably positioned in an elongated slot 23 formed through the inner end of a pull bar 24, the inner end of this slot 23 having an upwardly directed offset 25 which receives the pin 22 at one period in the operation of the device, as will be hereinafter described, the pin at certain periods riding from one end of the slot 23 to the other so as to permit an idling movement of the pull bar 24 without shifting the trays carried by the frame 16.

At their outer ends each of the pull bars 24 has pivotal connection, as at 26, with one end of an arm 27, which is secured rigidly to the adjacent inner face of the door 3 at an angle thereto, as shown.

From the descriptive matter thus far given it will be readily seen that when the door 3 is in closed position the bars 24 will be shoved in to the point where each pin 22 will be positioned in the forward end of a slot 23. The bars 24 when moved inwardly through the closing of the door 3 before reaching the limit of their inward movement will have the pins 22 engaged in the notches 25, but when the cams 15 are reached by the advancing rear ends of the bars they will ride thereon and thus raise the bars free from the pins, permitting movement of the bars the length of the slots 23 without affecting the frame 16.

At the forward end of the frame 16 there is suspended a cross bar 28 which at its ends has the upwardly directed arms 29 for connection with the side members 7 thereof. This cross bar 28 and the cross member 18 of the frame supports a rack 30 in close proximity to the bottom of the oven. Upon the inner face of each side member 17 of the frame 16 there is fixed adjacent the front and the rear ends thereof a pin 31.

These pins normally support on the frame 16 the transversely extending inverted substantially U-shaped frames 32, each of which comprises a cross bar 33 and depending side legs 34. The side legs 34 of the forward ones of these frames each has a downwardly directed recess in its end edge, as indicated at 35, while the legs 34 of the rear frame 32 each has a rearwardly directed recess in the rear edge adjacent the lower end thereof, as indicated at 36.

At their upper ends each of the legs 34 of the upper frames 32 has a hook 37 at its rear edge, these hooks being provided to support the tray 38, which is secured to the cross members 33 of the frames 32, in lowered position on the frame 16 as shown in Figure 1.

From the foregoing it will be seen that while the lower rack 30 is permanently disposed in the lower part of the oven and supported by the frame 16, the upper rack 38 may be either mounted on the frame 16 in the raised position shown in Figure 2, or in lowered position just described or it may be completely removed from the oven if a large receptacle is to be placed therein on the lower rack.

It will also be noted that the lower rack 30 is materially shorter than the upper rack 38 and while the rear edges thereof are in substantially the same vertical plane the forward edge of the lower rack sets in a considerable distance beyond the forward edge of the upper rack so that it will not come into contact with the door when the latter is swung open and the frame is drawn outwardly thereby. It will also be seen that when the door is first opened it will have short swinging movement before any pull is applied to the frame 16. This is allowed by the loose connection between pins 22 and the slotted inner ends of the pull bar 24.

Having thus described our invention, what we claim is:—

1. The combination with an oven having a swinging door, of a pair of tracks disposed at opposite sides of the oven upon the interior thereof, a frame having side members slidably carried by the tracks and having a cross rear member disposed in a plane beneath the side members, a supporting member suspended from said side members and located in substantially the same horizontal plane as the cross rear member of the frame, a tray carried by said cross members, and means connecting the door with said frame, whereby withdrawal of the frame and rack is effected when the door is opened and replacement of the same is effected when the door is closed.

2. The combination with an oven having a swinging door, of track members disposed therein and upon the side walls thereof, a frame having side members slidably mounted on said tracks, a link connection between the frame and said door whereby removal of the frame from the oven is effected when the door is opened and replacement of the frame in the oven is effected when the door is closed, means permitting swinging movement of the door in both the opening and the closing thereof without affecting the frame, inwardly projecting pin members carried by the side members of the frame, upstanding racks removably supported on said pin members, and a tray carried by said racks.

3. The combination with an oven having a swinging door, of track members disposed therein and upon the side walls thereof, a frame having side members slidably mounted on said tracks, a link connection between the frame and said door whereby removal of the

frame from the oven is effected when the door is opened and replacement of the frame in the oven is effected when the door is closed, means permitting swinging movement of the door in both the opening and the closing thereof without affecting the frame, inwardly projecting pin members carried by the said members of said frame, a pair of racks each of inverted substantially U-shaped formation and having the free ends of the side portions thereof formed to detachably receive said pins, a tray secured to and supported by said racks, and hook members carried by the racks adjacent the upper ends of the side members thereof for supporting the tray in lowered position upon said pins.

4. The combination with an oven having a swinging door, of track members arranged horizontally therein and upon the side walls thereof, a frame disposed between the tracks and having its sides slidably received thereby, means coupling the frame with the door whereby removal of the frame from the oven is effected when the door is opened and replacement of the frame in the oven is effected when the door is closed, a pair of inverted substantially U-shaped racks disposed transversely of the oven, a tray secured to and supported by said racks, and means for detachably connecting the side portions of said racks at selected points thereon, with the side members of said frame, to mount said tray in the oven in raised or lowered position with respect to the frame.

5. The combination with an oven having a swinging door, of a pair of tracks disposed at opposite sides of the oven, a frame of substantially U-shaped design disposed horizontally in the oven and having the side members thereof slidably supported upon said tracks, the portion of the frame connecting the side members being disposed at the rear of the oven and attached to the side members by integral portions depending therefrom, said frame having the forward or free ends of the side portions inset, a bar disposed transversely in the oven in substantially the same plane as the transverse portion of said frame and having upturned arms connected with the side members of said frame, a tray mounted upon said bar and the transverse member of the frame, and means connecting the side members of the frame with the oven door for reciprocatory movement with the frame, for effecting the shifting of the frame and tray with the swinging of the door.

In testimony whereof we hereunto affix our signatures.

60 ERNEST A. CHANDLER.
JOHN H. McCANN.
